UNITED STATES PATENT OFFICE.

ROBERT E. ZUENDT, OF LITTLE ROCK, ARKANSAS.

ROTARY EXPLOSIVE-ENGINE.

1,180,099.

Specification of Letters Patent. Patented Apr. 18, 1916.

Application filed April 30, 1915, Serial No. 24,887. Renewed February 28, 1916. Serial No. 31,059.

To all whom it may concern:

Be it known that I, ROBERT E. ZUENDT, a citizen of the United States, and a resident of Little Rock, in the county of Pulaski and State of Arkansas, have invented a new and useful Improvement in Rotary Explosive-Engines, of which the following is a specification.

My invention relates to new and useful improvements in rotary explosive engines using a mixture of gasolene and compressed air, and has for an object the provision of a device of the above character which will combine the advantages of a rotary engine with those of the ordinary type of reciprocating engines.

Another object of the invention is the provision of such device wherein the gas mixtures are compressed before being admitted to the explosion chamber.

A further object of my invention is the provision of such a device which will be positively operated thereby insuring a proper timing of each of the working parts and eliminating lost motion.

A further object is to provide means whereby the expense of manufacture will be materially lessened and the efficiency of the engine materially increased.

With these and other objects in view my invention consists in certain novel features of construction, arrangement and combination of parts as will be hereinafter described and pointed out in the claims, reference being had to the accompanying drawings, in which:

Figure 1 is a side elevation partly in section, Fig. 2 is a section substantially on line 2-2 of Fig. 1, Fig. 3 is an elevation partly in section, Fig. 4 is a diagrammatic view showing relative movement of the flap-valve and its operating cam, Fig. 5 is a section on line 5-5 of Fig. 2, Fig. 6 is a perspective view of a portion of the rotor carrying radial pistons.

Referring to the drawing, the casing is represented by 8 and consists of two similar sections or plates having annular channels, and which when bolted together form the annular impulse chamber 9 in which the

pistons 10 carried by the rotor 11 fit gas tight and are driven by the explosion of the gas mixture; the rotor 11 is a disk mounted between the sections or plates of the casing and is rigidly secured to the shaft 12 which passes through the casing and carries at one end the commutator or sparking device 13, and on the opposite side of the casing the cams 14 and 15 for operating the gate or flap valve 16 mounted on rock shaft 16^a and the sliding valve 17 respectively. The ignition chamber 18 is bolted to the casing at its upper part and has communication with the interior of the casing by the opening 19 which is controlled by the slide valve 17; a rock shaft 20 passes transversely through the ignition chamber 18 and carries at one end a crank arm 21 to which is connected the rod 22, the lower end of which is connected to one end of the lever 23 whose other end is pivoted to the outside of the casing and carries at about its center the friction roller 24 which is acted on by the cam 14. A tension spring 25 is also connected at one end to the crank arm and the other end anchored to the casing, as shown in Fig. 1.

On the opposite end of rock shaft 20 are the curved presser arms or tappets 26 and 27, the first of which acts on the plunger 28 of the gasolene pump 29 to permit charges of gasolene to enter the pipe chamber 30. On the same shaft 20 is the curved presser arm or tappet 27 which acts on air inlet valve 31, admitting air to pipe 30, the air passing through the check valves 30^a, mixing with gasolene and conveying the charge to the ignition or combustion chamber 18 through the check valve 30^b.

On the shaft 12 as stated is a cam 15, the function of which is to operate the flap valve or abutment 16, through the lever, 32, connecting rod 33 and crank arm 34 rigidly mounted on the rock shaft 16^a carrying the said flap valve 16, the said crank arm being attached to the tension spring 35 as shown in Fig. 1, said spring being anchored to the casing, the same as tension spring 25. Entering the top of the ignition chamber 18 is the spark plug 36 which is connected in 100

suitable manner to the commutator or spark timer 18. The flap valve or abutment 16 is mounted at one end in a recess 16^a communicating through opening 19 with chamber 18 and whose lower portion is flush and coextensive with internal circumference of the impulse chamber and of such depth that when the flap valve or abutment 16 is swung upward into said recess the piston 10 can 10 pass it freely.

In Fig. 1 the residue of a previously exploded charge is shown by arrows as being expelled and a new charge being admitted to the ignition chamber, compression is accomplished by the pressure of the compressed air only. As shown in Fig. 2 the air inlet valve and gasoline pump valve are both open to form a new charge which is admitted to the combustion chamber; the 20 new charge now having been formed and forced into the ignition chamber, it is about to be exploded as shown in Fig. 3; the residue of the previous charge is being forced out by one piston, while the other piston, 25 not now working, is compressing air in advance of it which will presently act as a scavenger. The slide valve 17 is now open through the action and relative position of the cam 14, giving communication between 30 the ignition chamber and the impulse chamber, or space included between the flap valve and the rear face of the piston 10, the valve 16 forming an abutment, the flap valve being dropped by the action of cam 15.

In Fig. 4 I have illustrated by diagram showing the cam 15 only, illustrating how flap valve 16 is just closing by reason of the declining surface of said cam 15, thus permitting compressed air in front of the idle piston to scavenge the cylinder of the previously burned charge which is shown as making its initial exhaust. The continued rotation of the upper piston 10, completely clears the piston chamber of all burned mixture. When the bent presser arm 26 releases the stem of the plunger 28 of the gasoline pump 29 so that it may return to its upper portion through agency of the spring 28^a, the plunger 28 draws more gasoline 50 into the cylinder through the back check valve 29^a shown at Fig. 2, and at the next downward stroke of the plunger 28 forces this gasoline past the spring seated valve 29^b into the chamber 30 where it is mixed 55 with the compressed air charge admitted by air inlet valve 31 from the air supply.

As shown in Fig. 6 the rotor 11 has the radial pistons 10 which extend beyond it on each side and each is provided with suitable 60 packing strips 10^a and 10^b on its side faces and outer face. It will of course be understood that the proportions and arrangement of the various movable parts are such that with the proper timing of the relative

movement of the various coacting parts, the 65 explosions are very rapid and that a high velocity of motion is given the engine shaft from which the power may be translated to various uses.

I claim:

1. A rotary explosive engine comprising a casing including an ignition chamber, and an impulse cylinder, an opening in the ignition chamber to receive the explosive mixture, a passage from said ignition chamber 75 to the impulse cylinder, a slide valve mounted on a rock shaft in said ignition chamber and controlling said passage, a recess in the casing in communication with said passage, a swinging abutment mounted on a rock 80 shaft in said recess, a crank arm mounted on said rock shaft, a crank arm mounted on the rock shaft actuating the slide valve, a rotor mounted on a main shaft within the casing, cams mounted on said shaft exteriorly of the casing, levers mounted at one end to the outer wall of the casing, rods at the opposite ends of the said levers connected to the crank arms of the respective rock shafts, said levers having projections 85 intermediate their ends adapted to contact with the cams on the main shaft, tension springs connected to the crank arms to the casing, and means carried by the slide valve 90 rock shaft for actuating a gasoline pump and an inlet valve, and force the mixture into the ignition chamber, and a radial piston member carried by the rotor to receive the impulse of the exploded charge and rev- 95 olubly drive said rotor.

2. A rotary explosive engine comprising a casing having an impulse chamber and a rotor having a radial piston member, an ignition chamber mounted on said casing, a passage from said ignition chamber to the 105 impulse chamber, a slide valve in the ignition chamber and controlling said passage, a rock shaft operating said slide valve and extending exteriorly of the ignition chamber, a swinging abutment in said impulse chamber, and means carried by the aforesaid rock shaft for actuating pump means for 110 supplying fuel to the said ignition chamber.

3. A rotary explosive engine comprising a casing having an annular impulse chamber and a rotor having a radial piston adapted to travel in said impulse chamber, an ignition chamber mounted on said casing, an inlet to convey compressed fuel gases to said ignition chamber, a passage 115 from the ignition chamber to the impulse chamber, a flap valve mounted in the impulse chamber and controlling the outlet from the ignition chamber on one side of the ignition chamber, a slide valve in the ignition chamber controlling said outlet within the ignition chamber, a rock shaft oper- 120 ably connected with said slide valve, a pipe 125

leading from an air supply to the inlet to the ignition chamber, a spring actuated valve controlling said pipe, a gasoline pump located on said pipe between the air inlet valve and the ignition chamber, tappets carried by the slide valve rock shaft for actuating the air inlet valve and gasoline pump to

form the explosive mixture, and means actuated by the rotor for actuating the rock shaft and the tappets carried thereby.

ROBERT E. ZUENDT.
